UNITED STATES PATENT OFFICE.

LEO F. ADT, OF ALBANY, NEW YORK.

EYEGLASS NOSE-GUARD.

No. 875,233.

Specification of Letters Patent.

Patented Dec. 31, 1907.

Application filed March 24, 1906. Serial No. 307,773.

To all whom it may concern:

Be it known that I, LEO F. ADT, of Albany, in the county of Albany and State of New York, have invented certain new and useful Improvements in Eyeglass Nose-Guards; and I do hereby declare the following to be a full, clear, and exact description of the same, reference being had to the accompanying drawings, forming a part of this specification, and to the reference-numerals marked thereon.

My present invention has for its object to provide an improved nose guard for eyeglasses which will not only serve to hold the mounting firmly in position on the wearer's nose, but which can be made at a minimum cost from a single stamping of flat sheet material such as gold or other metal and readily formed without unduly straining the material, all as will be hereinafter fully described, the novel features pointed out in the claims at the end of this specification.

In the drawings: Figure 1 is a perspective view of a portion of an eyeglass mounting with my guards applied thereto. Fig. 2 is a view of one of the guards detached, and Figs. 3 and 4 are perspective views of modified forms, of the guard detached.

Similar reference numerals in the several figures indicate similar parts.

My improved guard in all the forms shown is formed from a single stamping of sheet material, preferably metal, one portion indicated by 1 being so shaped as to fit into or upon the stud of an eyeglass mounting, and from this extend two arms, one indicated by 2 passing downwardly below the attaching portion and having a lower under part 3 constituting the lower pad or portion for bearing on the wearer's nose, and the other arm 4 being preferably more resilient and bent toward the edge of the stock so as to cross the lower arm above its pad and having the upper end under and constituting the upper pad or portion 5 for bearing on the wearer's nose nearer the eyes, so as to steady the glasses and prevent their tilting, the principal weight being sustained by the lower pads.

In the form shown in Figs. 1 and 2 the blank is first cut by dies from flat stock with the upper arm 4 and pad 5 at the side of the attaching portion as in dotted lines in Fig. 2. In this form also this upper arm joins the blank at some distance below the attaching portion 1, of the mounting and to form

the complete guard it is only necessary to offset the arm slightly which may be done when the blank is stamped or subsequently, and then bend the arm in the plane of the stock or edgewise of the metal forming the 60 loop 6. This arm is more or less resilient and being longer than the distance from the pad directly to the attaching portion will hold the guard and mounting with a grip that is sufficient for the purpose without being too rigid as the upper pad should always bear with a light yielding pressure on the portion of the nose which it engages. The surfaces of the nose-bearing portions which may be termed pads, are preferably roughened or corrugated as shown to afford a gripping surface and they may be rounded or bulged slightly as usual.

In the form shown in Fig. 3 the attaching portion of the guard is arranged intermediate the ends of the two arms and the arm bearing the upper bearing portion extends from the attaching part downwardly and then upwardly, but in this as in the other forms, said arm is bent edgewise of the stock, 70 crosses the lower arm and has a long spring portion, and the blank is formed from a single piece of material. The guard shown in Fig. 4 possesses the same characteristics as the others but the attaching portion also 75 forms the connection between the two arms, the lower arm extending over and downward from the upper part, and this might be found desirable in some instances, but I prefer the form shown in Figs. 1 and 2 as it is 80 symmetrical and is found in practice to be admirably adapted to the purpose intended.

I claim as my invention:

1. An eyeglass guard formed of flat stock embodying an attaching portion, a downwardly-extending arm having a free end forming a lower nose-bearing portion or pad thereon and a resilient arm bent in the direction of the edge of the stock crossing the downwardly-extending arm and having a 95 nose-bearing portion or pad arranged above the lower bearing pad or portion.

2. An eyeglass guard formed from a single stamping of sheet material embodying an attaching portion, an arm extending rearwardly and downwardly from said attaching portion and having a bearing pad or portion thereon and an arm extending directly from the attaching portion and bent in the direction of one edge of the stock crossing the 100

110

lower bearing arm and having the upper end formed into a bearing portion or pad for engaging the nose of the wearer.

3. An eyeglass guard formed from a single stamping of flat stock embodying the attaching end, the downwardly and rearwardly-extending arm having the lower bearing portion or pad at its lower end and the arm extending from the edge of the downwardly-

extending arm formed into a flat loop thence 10 crossing the downwardly-extending arm and extending above the latter, the end being widened to form the upper bearing pad or portion.
